Patented Mar. 2, 1909.

UNITED STATES PATENT OFFICE.

STILLMAN ARMSTRONG, OF VANCEBORO, MAINE.

MOCCASIN.

No. 914,220.

Specification of Letters Patent. Patented March 2, 1909.

Application filed February 27, 1908. Serial No. 418,028.

To all whom it may concern:

Be it known that I, STILLMAN ARMSTRONG, a citizen of the United States, residing at Vanceboro, in the county of Washington and 5 State of Maine, have invented new and useful Improvements in Moccasins, of which the following is a specification.

The present invention relates to foot coverings and particularly to that type known 10 as "moccasins."

It has for its object the provision of a moccasin of the "low quarter" style, in which the disposition of the lacing flaps insures the secure fastening of the moccasin against 15 looseness and slip; and, furthermore, such lacing flaps, together with the tongue, when arranged in accordance with my invention, afford a complete protection for the instep of the wearer; these results being accomplished 20 without adding materially to the weight or cost of the moccasin, and without detracting from its appearance or comfort.

In order that the invention may be understood by those skilled in the art I have illustrated in the drawings herewith one embodiment of my invention, and that the best now known to me.

In said drawings: Figure 1 is a perspective view of a moccasin constructed in accordance 30 with my invention, one of the lacing flaps being thrown to an upright position in order to show their construction, and the construction and arrangement of the tongue closure.

Fig. 2 is a central longitudinal sectional view 35 of the moccasin shown in Fig. 1, the heel portion being left in elevation. Fig. 3 is a transverse sectional view across the rear ends of the lacing flaps to show the manner of attaching these to the upper. Fig. 4 is a top 40 plan view of a portion of the moccasin to show the closure, the lacing flaps being opened for clearness of illustration. Fig. 5 is an enlarged detail view to show the manner of attaching the lacing flaps to the upper. Fig. 6 is an enlarged detail view of the 45 heel seam of the moccasin.

Referring to the drawings by numerals, like numbers indicating like parts in the several views, 2 indicates the sole and upper 50 portion of the moccasin, which preferably, and as herein shown, is formed of a single piece of suitable material the upper being of substantially uniform height, the blank from which it is formed being shaped to the 55 proper contour and having its heel portion cut and seamed together by an outturned

seam along the lines of an inverted T, so as to give the proper shape and overhang to the heel portion and take care of the undesirable fullness which would otherwise exist when 60 the moccasin is shaped up of a single piece of material.

Secured to the upper edges of the forward or toe portion of the moccasin 2 is the top section 3 of the moccasin, which is stitched to 65 the moccasin 2 by an outstanding seam, as shown in Fig. 2, in the same manner as the seams at the heel of the moccasin are formed, so that there are no inwardly projecting ridges to chafe the foot. This top section 3 is 70 stitched to the sole and upper portion 2 of the moccasin back to a point just above the instep and has a free rearwardly projecting portion 4 to which is secured, by stitching or in any suitable manner, a free tongue portion 75 5 which is preferably of relatively thin flexible stock, and which is not attached to the moccasin except where it joins the portion 4. It will be observed that by providing this free rearwardly projecting portion 4 of the 80 top section 3, and securing the tongue 5 to the edge of such rearwardly projecting portion, the stitching which joins the projecting part 4 and the tongue 5 is taken out of the natural line of flexure of the tongue closure 85 so that it is not subjected to the wearing incident to bending or pulling forward of the tongue, the natural line of the bend of the tongue portion being between the points 6, see Fig. 4. In order that this low cut moccasin may be firmly secured to the foot of the 90 wearer and held against any looseness or slip, and at the same time protection may be afforded the instep to guard it against injury in tramping through undergrowth or over 95 rough country, I provide the upstanding lacing flaps 7, which are independent of each other and preferably shaped as shown with their rear ends sloping gradually downwardly to the edge of the upper 2, and their forward 100 ends free and projecting forwardly so that they may be drawn over and across the instep above the tongue 5, thereby affording a very complete and close closure above the instep, while at the same time they effectively 105 secure the moccasin to the foot, it being understood that the usual lacing thongs will be used in the eyelets of the lacing flaps 7.

It will be observed that the lacing flaps 7 are secured at their lower edges to the upper 110 edges of the upper portion 2 on each side thereof, and the stitching which secures these

lacing flaps to the upper preferably terminates at a point substantially coincident with the point where the rearwardly-projecting portion 4 of the top section 3 begins, as 5 clearly shown in Figs. 1 and 2, so that the strain of opening the lacing flaps and the tongue closure for the insertion of the foot is centralized at one point, and this may be 10 strongly reinforced by increasing the stitching, or, as herein shown, and preferably, by providing a rivet 7' which is located at the corner of the lacing flap 7 at the point of greatest strain, so that the likelihood of separation of any of the parts in use may thus be 15 minimized. Furthermore, this arrangement provides for the ready opening and easy insertion of the foot without leaving any gaping openings when the moccasin is laced up, for the lacing flaps 7 extend beyond the free portion 4, and the tongue 5 and the forwardly projecting ends 8 of these lacing flaps 7 effectively cover this tongue closure when the boot 20 is laced up.

The lacing flaps 7 are independent of each 25 other in that they do not extend around the heel portion of the moccasin, but extend upwardly on either side thereof between the heel and toe of the moccasin at or about the line of the instep so that they naturally stand 30 in a proper position for lacing across and about the instep, and this position of the lacing flaps 7 coupled with the fact that they are provided with the free forwardly extending portions 8, provides a moccasin which 35 may be securely laced and held to the foot without the necessity of providing an upwardly extending heel portion as is common.

In order that the exterior of the moccasin 40 may be smooth and finished I preferably chamfer or thin the lower edges 9 of the lacing flaps as shown in Figs. 1, 3 and 5, and then, in order to secure the parts properly, I provide a plurality of lines of stitching through the edge of the upper and the thin 45 portion of the lacing flaps, as clearly shown in Fig. 5 and this results in giving a smooth exterior without sacrificing any of the strength of the securing means.

By forming a moccasin, in the manner 50 shown, of a single piece of material so far as the sole and upper portion is concerned, and shaping the heel by means of the outturned inverted T-shaped seam and joining the top 55 section 3 by the same style of seam, a moccasin having an absolutely smooth interior is provided and all danger of chafing the feet is eliminated.

By providing the top piece 3 with a rear-

wardly-projecting portion 4, and securing the tongue proper 5 to the rearwardly projecting portion, I take the line of bend or flexure on which the tongue is manipulated away from the stitching and eliminate the danger of strain and wear upon this stitching. 60

By providing the up-standing forwardly projecting lacing flaps on each side of the upper I secure a very effective closure, and one which, in connection with the tongue closure, will protect the instep against injury and will also prevent the ingress of dirt, 70 twigs, and the like, to the moccasin in working through a rough country; and, furthermore, the overlapping and projecting lacing flaps form a most effective securing means which will hold the moccasin on the foot 75 without slip or looseness, and it will be observed, further, that the sloped-off rear portions of the lacing flaps are so merged into the line of the top of the moccasin that a very pleasing and comfortable heel portion 80 is provided and one which will not extend too high on the heel of the wearer so as to cause annoyance or chafing.

It is obvious that some slight changes 85 may be made in the moccasin which I have invented within the skill of the maker without departing from my invention and I do not therefore, limit myself to any of the details shown and described except so far as I am limited by the prior art to which the 90 invention belongs.

Having fully disclosed my invention, I claim:—

A moccasin comprising a sole and upper portion formed of a single piece of material, 95 a top piece formed of a separate piece of material and secured to said upper portion, said top piece having a free portion at its end adjacent the instep and constituting a portion of the tongue of the moccasin, an 100 independent piece secured to said free portion and constituting the remaining portion of said tongue, and a pair of flaps secured to the side edges of said upper and adapted to have their inner edges meet centrally of and 105 overlap the tongue, the rear ends of said flaps sloping back to the heel portion of said upper whereby to provide a substantially sealed closure for the foot.

In testimony whereof I have hereunto set 110 my hand in presence of two subscribing witnesses.

STILLMAN ARMSTRONG.
